UNITED STATES PATENT OFFICE.

AARON NEISWENDER, OF ORWIGSBURG, PENNSYLVANIA, ASSIGNOR OF ONE-HALF TO
HOWARD W. WESTON, OF POTTSVILLE, PENNSYLVANIA.

METALLIC RAILROAD-TIE.

1,223,895.

Specification of Letters Patent. Patented Apr. 24, 1917.

Application filed November 26, 1915, Serial No. 63,643. Renewed September 27, 1916. Serial No. 122,549.

To all whom it may concern:

Be it known that I, AARON NEISWENDER, a citizen of the United States, residing at Orwigsburg, in the county of Schuylkill and 5 State of Pennsylvania, have invented certain new and useful Improvements in Metallic Railroad-Ties; and I do hereby declare the following to be a full, clear, and exact description of the invention, such as will 10 enable others skilled in the art to which it appertains to make and use the same.

The invention relates to improvements in metallic cross ties for railroads.

The object of the present invention is to 15 improve the construction of metallic cross ties and to provide a simple, practical and comparatively inexpensive cross tie designed particularly for use on bridges and other places where wooden cross ties are liable to 20 be destroyed by fire and adapted to afford the resiliency of a wooden cross tie without liability of breaking the fastening means and capable of enabling the gage of the rails to be readily corrected when required.

25 With these and other objects in view the invention consists in the construction and novel combination and arrangement of parts hereinafter fully described, illustrated in the accompanying drawings and pointed out in the 30 claims hereto appended, it being understood that various changes in the form, proportion and minor details of construction may be resorted to without departing from the spirit or sacrificing any of the advantages of the invention.

In the drawings

Figure 1 is a plan view of a metallic cross tie constructed in accordance with this invention, one of the rails being in section, 40 Fig. 2 is a central longitudinal sectional view,

Fig. 3 is an end elevation of the same partly broken away,

Fig. 4 is a transverse sectional view on 45 the line 4—4 of Fig. 2,

Fig. 5 is a detail perspective view of one end of the cross tie the top plate being removed,

Fig. 6 is a detail perspective view of the 50 bottom portion of one end of the cross tie,

Fig. 7 is an enlarged detail sectional view illustrating the arrangement of the fastening means for holding the rail in position.

Like numerals of reference designate cor-

responding parts in the several figures of 55 the drawings.

In the accompanying drawings in which is illustrated the preferred embodiment of the invention, the metallic cross tie comprises in its construction a pair of I beams 60 1 consisting of vertical webs and top and bottom flanges 3 and 4, fitted together as clearly illustrated in Fig. 5 of the drawings and connected by top and bottom plates 5 and 6 riveted or otherwise secured to the 65 top and bottom flanges of the I beam. The cross tie is particularly designed for use on bridges and other structures liable to destruction by fire and where wooden cross ties are a menace and the bottom plate 70 is provided with transverse flanges 7 preferably consisting of angle strips secured to the lower face of the bottom plate and projecting downwardly therefrom so as to engage the stringers or beams of the bridge or other 75 structure. These flanges are also adapted to engage the road bed to prevent the said cross tie from slipping.

The top flanges 3 of the I beam are recessed between their ends to provide longitudinal slots 9 located at the end portions of the cross tie and adapted to receive rods 10 and 11 which extend through slots 12 and 13 of the top plates for engaging the bottom flanges of the rails 14 at the inner 85 and outer sides thereof as clearly illustrated in Fig. 7 of the drawings. The rods 10 and 11 are arranged at an inclination and are provided at their upper engaging ends with hooks 15 and 16 which embrace the said 90 bottom flanges of the rails. The outer rods 10 pierce end plates 17 and are threaded for the reception of nuts 18. The end plates 17 extend across the ends of the webs of the I beams and have angularly bent terminal 95 attaching portions 19 which are riveted or otherwise secured to the webs 2 of the I beam. The lower ends of the inner rods 11 extend to the central portion of the tie and pierce vertical plates 20 extending downwardly from the top of the cross tie at the ends of an opening 21 formed by cutting away the top flanges between the webs of the I beams as clearly illustrated in Fig. 4 of the drawings. The top plates extend to 100 and terminate at the opening 21 and the vertical plates 20 are provided at their upper and lower ends with oppositely extend-

ing flanges 22 and 23. The upper flanges 22 extend outwardly and project over the inner ends of the top plates 5 while the lower flanges 23 extend inwardly and are over-
5 lapped and secured to the bottom flanges 4 by rivets 24 or other suitable fastening de-
vices. The inner rods 11 which project into the pocket or recess 25 are threaded for the
reception of nuts 26 which engage the inner
10 faces of the vertical plates 20. By adjust-
ing the rods it will be seen that the gage of the rails may be corrected. The fastening
device for securing the rails to the cross tie effectively prevents the rails from spreading
15 or moving upwardly and at the same time
may permit a longitudinal movement of the
rails due to expansion and contraction. The
nuts of the outer rods are exposed at the
20 ends of the cross tie while ready access may
be had to the nuts of the inner rods at the
pocket 25 which is open at the top.

The metallic cross tie may be equipped
with additional rail engaging means con-
sisting of clamping plates 27 engaging the
25 bottom flanges of the rails at opposite sides
thereof and adjustably secured to the cross
tie by bolts 28 or other suitable fastening
means which pass through slots 29 in the
clamping plates and pierce the top plates
30 of the cross tie and the top flanges of the I
beams.

What is claimed is:—

1. A metallic cross tie including a pair of
I beams arranged side by side and hav-
35 ing their upper and lower flanges fitted to-
gether, the upper flanges being cut away
between the webs to form intermediate and
end openings, end plates secured to the webs
of the I beams, spaced plates located at the
40 intermediate opening and inner and outer
rods piercing the intermediate and end open-
ings of the said top flanges and provided
thereat with means for engaging a rail at
45 the inner and outer sides thereof.

2. A metallic cross tie including a pair of
I beams arranged side by side and having
their upper flanges cut away at the ends and
at the center to form openings, top plates se-

cured to the upper flanges and provided at 50
the end openings with slots and terminating
at the central opening, vertical plates ar-
ranged in the central opening and provided
at their upper and lower edges with oppo-
55 sitely extending flanges, the upper flanges
engaging the top plates and the lower flanges
being secured to the bottom flanges of the I
beams, end plates connecting the webs at
the ends of the I beams, inclined rods pierc-
60 ing the end plates and the vertical plates
and provided with means for engaging the
same and having terminal hooks located at
the end openings of the I beams and the slots
of the top plates and arranged to engage the
65 rails at the side edges thereof.

3. A metallic cross tie including spaced
beams having vertical webs and upper and
lower horizontal flanges fitted together, the
upper horizontal flanges being cut away at
the ends and at an intermediate point to 70
form end slots and an intermediate opening,
upright plates or members mounted in the
intermediate opening, and rods piercing the
upright plates and adjustably connected
75 with the same and extending therefrom to
the end slots and provided thereat with
means for engaging the base of a rail.

4. A metallic cross tie including beams
having vertical webs and upper and lower
horizontal flanges and arranged side by 80
side, the upper horizontal flanges being cut
away at the ends and at an intermediate
point to form end slots and an intermediate
opening, upper plates secured to the upper
85 flanges and extending from the end slots to
the intermediate opening and adapted to re-
ceive the rails, upright plates or members
mounted in the intermediate opening at the
ends thereof and fastening devices extend-
ing from the upright plates to the end slots 90
and provided with means for engaging the
rails at the base thereof.

In testimony whereof I affix my signature
in presence of two witnesses.

AARON NEISWENDER.
